UNITED STATES PATENT OFFICE.

CHARLES G. COOPER, OF MOUNT VERNON, OHIO.

TRACTION-ENGINE.

SPECIFICATION forming part of Letters Patent No. 225,050, dated March 2, 1880.

Application filed January 20, 1880.

To all whom it may concern:

Be it known that I, CHARLES G. COOPER, of Mount Vernon, county of Knox, in the State of Ohio, have invented certain new and useful Improvements in Traction-Engines, of which the following is a specification.

My invention has relation to a traction or road engine of the kind described in my Letters Patent No. 218,714, dated August 19, 1879—that is to say, an engine in which motion is communicated from the motor to power-driven truck-wheels through the intermediary of a double-acting automatic pawl-and-ratchet mechanism.

15 I have in some respects improved and simplified the construction of what is called the "reversing disk" in my aforesaid Letters Patent.

I have also devised a different way of obtaining the friction which is requisite in order 20 to cause said disk to operate the pawls, and have modified the arrangement of the disk with respect to the pawl-carrier.

25 The nature of my improvements and the manner in which the same are or may be carried into effect may best be explained and understood by reference to the accompanying drawings, in which—

Figure 1 is a plan of so much of a traction-engine embodying my improvements as needed 30 to illustrate my invention. Fig. 2 is a transverse vertical section through one of the power-driven truck-wheels and parts adjacent thereto on line $x x$, Fig. 3. Fig. 3 is a longitudinal vertical section through the pawl-and-ratchet mechanism of said truck-wheel on line $y y$, Fig. 2.

I have here represented the pawl-and-ratchet mechanism as mounted on the axle of the power-driven truck-wheels. It may, however, 40 be mounted on the intermediate shaft, as represented in my above-named Letters Patent.

The truck-wheels I are mounted loosely on their axle. This axle may extend from side to side of the engine through the fire-box, or 45 preferably may consist of two short pieces, J , one on each side of the fire-box, on which the truck-wheels are loosely mounted. Each power-driven truck-wheel is provided with its own independent pawl-and-ratchet device, and a 50 description of one will answer for both.

Upon the hub of each wheel I is mounted a

gear-wheel, A , carrying the pawls which communicate movement to the truck-wheels. These pawls $a a'$ are arranged in pairs, the pawls of each pair being placed in opposition, 55 so that one will engage and act on the ratchet in a direction opposite to that on which the other will act. The ratchet is represented at B , formed in one with or attached rigidly to the truck-wheel I , and having square notches, as 60 shown, so as to engage either pawl. The pawls have their pivots in bosses carried by an overhanging rim, C , attached to or formed in one with the gear-wheel A .

Between each pair of pawls is a reversing-tongue, b , which is attached to the reversing-disk D , and at its outer end projects horizontally between the spokes $c c'$ of the pawl-carrying wheel C , so as to enter the space between the pawls $a a'$. The hub of the reversing-disk 70 is mounted to revolve on an enlargement, J' , of the axle J , and is held in place between the hub of the wheel C and a flange, J^2 , on the part J' , so as to be incapable of movement lengthwise.

In order to obtain friction between the reversing-disk and the axle, I form in the inner face of its hub one or more recesses, d , to contain blocks of Babbitt metal or other suitable material, which, by screws e , are pressed against 80 the axle J' , in order to obtain the requisite friction between the parts.

The gear-wheels C are driven by pinions E on the intermediate shaft, F , which, through the intermediary of the inclined shaft G and 85 suitable gearing, is driven from the engine-shaft H .

According to the direction in which the reversing-tongue b is moved, it will raise the pawl a or a' away from the ratchet and allow the 90 one not raised to drop into engagement with said ratchet.

In Fig. 3 the parts are represented as revolving in the direction indicated by the arrow, in which position the pawl a is in engagement with the ratchet and the pawl a' is raised by the tongue b of the reversing-disk, which is compelled to revolve by reason of the spoke c' of the wheel C , which comes against the tongue. If, now, the motion of wheel C be reversed the pawls $a a'$ will partake of the movement, but the reversing-disk

will not until the wheel C has moved far enough to bring its opposite spoke, *c*, up against the tongue *b*; but during the time the reversing-disk has remained at rest the pawls have traveled far enough to cause the rear pawl, *a*, which before was in front, to be raised by the tongue out of engagement with the ratchet, and to permit the opposite pawl, *a'*, to get clear of the reversing-tongue, and so drop into engagement 5 with the ratchet, thus compelling the reverse movement of the truck-wheel.

The space between each pair of spokes *c c'* is just sufficient to permit the above action of the reversing-disk, allowing it to rest long 15 enough to reverse the pawls, and then carrying it around with the wheel C in position to again reverse the pawls, when the direction of movement is again changed.

The pawls preferably are pressed toward 20 the ratchets by springs S, as shown. I propose, however, to use with the pawls a spring arrangement similar to that used in reapers and mowers, in which each pawl has an attached spring whose free end can be moved 25 to one side or the other of a projection, the spring serving either to hold up the pawl or to press it down, according to the side of the projection to which its free end may be brought. This arrangement would be of advantage in 30 that, if it should be desired to haul the engine by animal power alone, the pawls could be lifted by hand, and would be held by their springs in this position until again depressed.

Having described my said invention and 35 the manner in which the same is or may be

carried into effect, what I claim, and desire to secure by Letters Patent, is—

1. The combination, with the rotating pawl-carrier and one or more pairs of pawls carried by the same, of the reversing-disk, capable of 40 a movement of partial rotation independently of the pawl-carrier, and provided with one or more tongues, projecting one between each pair of pawls, and a friction device to retard the movement of the said disk when the latter is not engaged with the pawl-carrier, substantially as hereinbefore set forth. 45

2. The rotating reversing-disk, provided in its hub with one or more friction-blocks, in combination with means, substantially as described, for pressing said blocks more or less closely against the journal or axle on which said disk moves, substantially as and for the purposes set forth. 50

3. In an automatic double-acting pawl-and-ratchet mechanism operating substantially as described, a pawl-carrying wheel provided with spokes, spaced as specified, in combination with a reversing-disk provided with a tongue which projects through the wheel between said 60 spokes into the space between the pair of pawls on said wheel, substantially as and for the purpose set forth.

In testimony whereof I have hereunto set my hand this 5th day of January, 1880.

CHAS. G. COOPER.
